UNITED STATES PATENT OFFICE.

ALBERT ROSENBERG, OF BALTIMORE, MARYLAND.

GAS-ENGINE.

SPECIFICATION forming part of Letters Patent No. 593,859, dated November 16, 1897.

Application filed May 1, 1896. Serial No. 589,881. (No model.)

To all whom it may concern:

Be it known that I, ALBERT ROSENBERG, a citizen of the United States, residing at Baltimore, State of Maryland, have invented 5 new and useful Improvements in Gas-Engines, of which the following is a specification.

This invention relates to gas-engines, and has for its object to provide improved means 10 for regulating the speed of the engine, to provide improved means for exploding the gas, to provide improved exhaust mechanism, to provide an improved water-jacket for the cylinder, and, finally, to improve and simplify 15 this class of engines generally.

To these ends my invention consists in the features and in the construction, arrangement, or combination of parts hereinafter described, and pointed out in the claims following the description, reference being had to the accompanying drawings, forming a part of this specification, wherein—

Figure 1 is a side elevation of my improved engine, the gas-supply valve being shown in section. Fig. 2 is a vertical sectional view of the cylinder, illustrating the water-jacket, the igniter, and the exhaust and air-inlet valves. Fig. 3 is a view in elevation of the igniter-tube. Fig. 4 is a vertical sectional 20 view of my improved governor. Fig. 5 is a detail perspective view of the tappet for operating the gas-supply valve and a portion of the governor-spindle, and Fig. 6 is a detail sectional view of a modification.

Referring to the drawings, the numeral 1 indicates the engine-bed, having mounted thereon the working cylinder 2, engine-shaft 3, and wheel 4. A piston 5 is adapted to reciprocate in the cylinder 2, and its pitman 6 30 is connected to a crank 7 on the engine-shaft in the usual manner.

The numeral 8 indicates the gas-supply chest, connected with a gas-supply pipe 9 and communicating with the end of the cylinder 45 2 by a port or passage 10. Seated upon a suitable valve-seat in the gas-supply chest 8 is a valve 11, that opens outward relatively to the cylinder to permit the gas to enter the cylinder and is normally held closed by a 50 spring 12, said spring being of sufficient power to hold the valve closed at all times,

excepting when positively opened by the governor mechanism hereinafter described.

Supported in any suitable manner upon the cylinder is a casing 13, open at its upper end and inclosing the governor mechanism. Arranged centrally within the casing 13 is a vertically-movable spindle 14, supported in bearings 15 and 16. The bearing 15 consists of a recessed boss 17, forming the hub of a 60 spindle 18, attached to the casing and having balls 19 arranged in said recessed boss and forming an antifriction-bearing for the spindle, said balls being held in place by a gland 20, screwed into the boss. The bearing 16 is 65 formed in a manner similar to the bearing 15 and is attached to the bottom of the casing 13. Arranged upon the upper end of the casing is a spider 21, through the hub of which is tapped an adjusting-screw 22, having a reduced portion 23, that enters a hollow 70 reduced portion 24, formed on the upper end of the spindle 14, and serves to center said spindle. Arranged on the reduced portions 23 and 24 are washers 25 and 26, between 75 which is disposed a coiled spring 27, that normally operates to force and hold down the spindle 14. The spindle is supported in position by a coiled spring 28, that rests at its lower end on the gland 20 of the bearing 15, 80 and at its upper end bears against a washer 29, arranged on the spindle and on which rests an inverted cup-shaped hood 30, fixed on the spindle.

Upon the upper end of the spindle 14 is 85 fixed a fan consisting of a plurality of propeller-shaped blades 31, said fan rotating and rising and falling with the spindle. The spindle is rotated by a pulley 32, splined thereon and journaled in a spider 33, fixed in the casing 13. The pulley 32 is driven by a cord or belt 35, that in turn is driven by the engine-shaft or other moving part of the engine. It will thus be seen that the pulley and spindle are caused to rotate together, while the spindle may be moved vertically within the pulley. 95

An eccentric 36 is geared to the engine-shaft in such manner that it makes one revolution to every two revolutions of said shaft, and by means of the eccentric-rod 37 communicates a reciprocating movement to a rod 38, mounted in bearings 39, attached to the cyl-

inder. Pivoted to the free end of the rod 38 is a centrally-slotted tappet 40, that straddles the lower end of the governor-spindle 14 and is supported thereon by a washer 41, resting on a pin 42, passing through said spindle. The tappet 40, as it is reciprocated by the rod 38, alternately engages and disengages the head 43 of the stem of the gas-supply valve 11 and operates to open said valve once in every four strokes of the piston, as will hereinafter appear, to admit a charge of gas to the cylinder. The spindle 14 being rotated by the engine, should the speed of the latter become excessive the rotary fan 31, reacting upon the air within the casing, will rise, carrying with it the spindle, and thus raises the tappet 40 out of the path of the head of the gas-supply valve, so that said tappet will not operate to open said valve until the speed of the engine is reduced and permits the spindle 14 to drop. A spring 44 is fixed at one end to the end of the rod 38 and at its other end is provided with a set-screw 45, which bears against the upper side of the tappet 40. The purpose of said spring will be hereinafter described. The hood 30 serves to prevent dust and dirt from settling or being blown into the bearings beneath it, and a similar hood 30^a may also be arranged over the casing 13. Supported upon the inlet end of the cylinder 2 is the igniter-tube, consisting of a hollow tube or cylinder 46, closed at its upper end and at its lower end attached to the cylinder and registering with the interior thereof through a port 47. Said igniter-tube upon one side is provided with a countersunk aperture 48, over which is secured a diaphragm 49. Said diaphragm is preferably formed of platinum or similar non-fusible material and is seated in the countersink surrounding the aperture 48 and firmly secured in place by a washer 50, attached to the igniter-tube by means of screws or bolts. The diaphragm 49 is packed to its seat with a packing 51, of asbestos or similar non-conductor of heat, to prevent the heat being communicated to the igniter-tube from the diaphragm, and said diaphragm is preferably made cup-shaped, the convex side projecting inward toward the interior of the igniter-tube. Arranged directly in front of the diaphragm 49 is an injector-burner 52, comprising a shell having a contracted discharge end 53 and connected by a pipe 54 with the governor-casing 13. A tapered nozzle 55 is arranged centrally within the shell 52, its tapered end terminating near the contracted discharge end of said shell. A gas-pipe is connected to the rear end of the nozzle 55 and is tapped into the gas-supply pipe 9. The injector-burner operates to heat the diaphragm 49 and ignite the gas in the manner more fully hereinafter described.

To permit the escape of the smoke and burned gases after each explosion in the cylinder, I provide the latter at its closed end

with an exhaust-port 57, over which is secured a valve-casing 58, in which is seated an outwardly-closing valve 59. The valve 59 is provided with a stem 60, that projects through the casing 58, and about said stem is coiled a spring 61, that normally holds the valve closed on its seat, said spring being of sufficient strength to hold the valve closed at all times, excepting when positively opened by the means hereinafter described. For opening the valve I provide the following mechanism: Pivoted to a suitable support is a rocking lever 62, that at one end is adapted to engage the head of the valve-stem 60 and at its other end is pivotally connected to a link 63, that is in like manner connected to one end of a rocking lever 64, pivoted to the side of the cylinder. The free end of the rocking lever 64 is adapted to be engaged periodically by a tappet 65, carried by the reciprocating rod 38 and racked in such manner as to open the valve 59, as will more fully hereinafter be made apparent.

A valve 66, similar in construction to the exhaust-valve 59, controls an air-inlet port 67 in the end of the cylinder, the spring on said valve permitting it to open by atmospheric pressure when there is a partial vacuum in the cylinder—that is to say, while the cylinder is taking its supply of gas—for the admission of atmospheric air for admixture with the gas in the cylinder.

Surrounding the cylinder is a water-jacket 68, preferably constructed of a material forming a good conductor of heat—such as brass, for example. The water-jacket 68 is formed entirely separate from the cylinder 2 and consists of two concentric cylinders 69 and 70, united at one end by a head 71 and forming an annular chamber 72. The flange 73 of the cylinder 2 is provided with an annular rib 74, over which is seated the open end of the water-jacket, said jacket also being provided with a flange 75, which is tightly secured to the flange 73 of the cylinder by bolts 76. In order to fit the open end of the water-jacket to the cylinder water-tight, suitable packing 77 is interposed between the ends of said jacket and the flange 73. Water inlet and outlet pipes 78 and 79 are connected to the top and bottom, respectively, of the water-jacket and operate to maintain a circulation of water through the jacket in the usual manner. By forming the water-jacket separate from the cylinder and attaching it in the manner shown all danger of leaking of water from the jacket into the cylinder is avoided, while at the same time the jacket may be removed from the cylinder in case of necessity without disturbing the latter. Furthermore, by forming the jacket of a material of good conductivity the cylinder is quickly brought to and maintained at a uniform and even temperature.

The operation of my improved engine is as follows: During the operation of the engine

the governor-spindle 14 and its attached fan 31 are continuously rotated by the cord or belt 35, the speed of such rotation varying with the speed of the engine. The governor is set 5 or adjusted by adjusting the tension of the spring 27 by means of the set-screw 22 or by adjusting the tension of the spring 44 by its set-screw 45 to cause either of said springs to resist with a determinate pressure the lifting 10 force of the fan 31, caused by the blades of said fan reacting against the air as they rotate. As long as the engine runs at or below a certain speed, and hence as long as the fan is rotated at a relatively-corresponding speed, 15 the downward thrust of either of said springs will be sufficient to hold the governor-spindle 14 in its lowermost position, in which position it will support the tappet in a horizontal position, so that the tappet will periodically 20 engage the stem 43 of the gas-supply valve 11 and open said valve to admit successive charges of gas to the cylinder. Should, however, the speed of the engine become excessive, the increased rapidity with which the 25 fan rotates causes the latter to react against the air with such force as to cause the fan to ascend against the downward thrust of the springs and raises the spindle 14, thus lifting the tappet 40 out of the path of the stem of 30 the valve 11, whereby said tappet fails to engage the valve-stem and the supply of gas is cut off from the cylinder until the speed of the engine again becomes normal, when the governor-spindle is again forced down, lowering 35 the tappet into operative position and causing the gas-supply valve to be periodically opened, as before described. If it becomes necessary to utilize the maximum speed or power of the engine, both the springs 27 and 40 44 may be placed under tension to place a heavy load on the governor.

In addition to the fan operating as a governor for regulating the speed of the engine it also operates as a means for furnishing a 45 continuous blast of air to the injector-burner 52, the blades of the fan forcing the air downwardly in the casing 13, whence it escapes through the pipe 54 into the shell of the burner 52 and issues from the contracted discharge 50 end of the latter intimately mixed with the gas issuing from the nozzle 55. The blast of mixed gas and air, being ignited at the discharge end of the burner, impinges in the form of a flame of great intensity against the 55 diaphragm 49 on the igniter-tube and heats said diaphragm red-hot, so that the gas when it is compressed in the cylinder, as herein-after described, is ignited.

The operation of the governor and igniter 60 having now been described, the operation of the engine will be readily understood. Let it be assumed that the engine is running at normal speed and that a charge of gas has just been compressed and exploded in the 65 cylinder. The piston 5 will then be driven forward on what I shall call, for the sake of explanation, the "first" stroke, and at the

completion of said stroke will have turned the engine-shaft 3 and its wheel 4 one-half of a revolution. All the different parts of the engine will then be in the position shown 70 in Fig. 1. During this half-revolution of the engine-shaft the eccentric 36 has been rotated one-fourth of a revolution and during the final part of said partial revolution has moved the 75 reciprocating rod 38 forward, causing the tappet 65 to engage the end of the lever 64 and rock the same into the position shown in Fig. 1. The rocking lever 62, through the medium of the link 62, is rocked in a corresponding direction, opening the exhaust-valve 59, so that the smoke and burned gases are expelled as the piston moves on its return or second stroke. During this second stroke the engine-shaft completes its second half-revolution, rotating the eccentric 36 a second 80 quarter-revolution, which moves the rod 38 backward, the exhaust-valve gradually closing as the piston completes said stroke, so that at the end of the stroke the said exhaust-valve is completely closed. By this time the 85 tappet 40 will have engaged the stem of the gas-supply valve 11, and as the piston moves on the next or third stroke, which is again in an outward direction, the gas-supply valve 90 is first opened and then closed, admitting a charge of gas into the cylinder. During this stroke the air-inlet valve 66 opens, admitting air into the cylinder with the gas. At the end of this stroke the valve 66 will automatically close. Upon the return or fourth stroke 95 of the piston the gas and air in the cylinder is intermixed and compressed, and at the end of this stroke the gaseous vapor will have been compressed to such a density that the 100 red-hot diaphragm in the igniter-tube will 105 ignite the same and cause it to explode, driving the piston forward, as before. Briefly stated, then, on the first stroke the piston is 110 driven forward by the explosion, on the second stroke the smoke and burned gases are expelled, on the third stroke the gas and air are admitted, and on the fourth stroke the gas is compressed and at the end of the stroke exploded.

I have described my governor as being applied to a gas-engine, but it will be readily apparent to those skilled in the art that it may be employed as a speed-governor for all kinds of engines or motors. I have also described the engine as using gas as the motive power, but I wish to be understood as including in the term "gas-engine" explosive-engines of all kinds.

While I have shown the governor inclosed 125 within a casing and furnishing a blast of air for a blowpipe or injector-burner, it will be evident that the casing and blowpipe may be dispensed with.

While I have shown the governor as furnishing the blast for heating the igniter, I 130 may use a separate blower or bellows for this purpose.

I may fill the cup in which the fan rotates

with glycerin, or an oil instead, for the medium air with which to govern the engine, and I wish to be understood as regarding a fluid of any kind as being the full equivalent of atmospheric air. When a liquid is employed instead of air, the casing 13 will not be connected with the injector-burner, but will be closed at its bottom, and the fan will be fitted to the lower end of the spindle, so as to rotate in the bottom of the casing, the drive-pulley being arranged above the casing, as shown in Fig. 6. In this form of device the valve-spindle will be arranged beneath the tappet 40. The operation is the same as that before described.

Having described my invention, what I claim is—

1. In a gas-engine, the combination with the cylinder and a self-closing gas-supply valve therefor, of a pivoted reciprocating tappet actuated by the engine for periodically engaging and opening said valve, a vertically-movable, rotatable spindle supported on a yielding support and connected to said pivoted tappet, a rotary fan having inclined blades fixed on said spindle and operating to lift the same by the reaction of the fan against the atmosphere to throw the valve-operating mechanism out of operation, a spring for normally holding said tappet in position for engaging the valve, and means for adjusting the tension of said spring, substantially as described.

2. In a governor for gas-engines, the combination with fixed bearings 15 and 16, of a vertically-movable, rotatable spindle 14 journaled therein and having splined thereon a driving-pulley 32 journaled in a fixed bearing, a rotary fan 31 having inclined blades fixed on said spindle and operating to lift the spindle by reacting against the atmosphere, an adjustable spring 27 for normally holding said spindle down, a hood fixed on the spindle above the said fixed bearings, and valve-operating mechanism thrown into and out of operation by the vertical movement of the spindle, substantially as described.

3. In a gas-engine, the combination with the cylinder, a self-closing gas-supply valve 50 11, and a normally-closed exhaust-valve 59, of a reciprocating rod 38 actuated by the engine, a tappet 40 pivoted to said rod and normally held in position for engaging the valve 11 to periodically open the latter, a rocking lever 62 adapted to engage the valve 59, a rocking lever 64, a link 63 connecting said levers, a tappet 65 on the rod 38 arranged to periodically engage the lever 64 and open the exhaust-valve, and a speed-governor driven 60 by the engine for throwing the tappet out of the path of the gas-supply valve when the speed of the engine becomes excessive, substantially as described.

4. The combination in a gas-engine, of a cylinder, an igniter-tube, an injector-burner

for delivering a jet of flame against said tube, and a fan-governor provided with an inclosing casing having an air inlet and an outlet pipe leading to the injector-burner, substantially as described.

5. In a gas-engine, the combination with the cylinder 2 provided at one end with an annular flange 73, of the water-jacket 68 surrounding said cylinder and having two concentric walls 69 and 70 and a head 71, an annular flange 75 on the end of the wall, and means for securing the open end of the water-jacket to the flange 73 of the cylinder, substantially as described.

6. The combination with a motor, of a speed-governor comprising a rotary fan driven by said motor and arranged to move in a line coincident with its axis of rotation, a speed-regulating device connected with said governor and controlled by the axial movement 85 of the latter, and a casing inclosing the governor and adapted to inclose the medium in which the governor revolves, substantially as described.

7. In a governor for gas-engines, the combination of a rotatable, lengthwise-movable spindle journaled in fixed bearings, a pulley loosely splined on said spindle and journaled in bearings independent of the spindle-bearings, means for driving said pulley, and a rotary fan fixed to said spindle and operating to lift the latter.

8. In a governor for gas-engines, the combination with fixed bearings, of a vertically-movable, rotatable spindle journaled therein, 100 means for rotating the spindle, a rotary fan fixed on the spindle, and a hood fixed on the spindle above the fixed bearings, substantially as described.

9. In a governor for gas-engines, the combination of a spindle, a fan fixed on the spindle, means for driving the spindle, and separate ball-bearings in which the spindle is journaled and in which it is revolvably and lengthwise movable, substantially as described.

10. In a gas-engine, the combination with the cylinder and a self-closing gas-supply valve therefor, of a reciprocating rod actuated by the engine for periodically engaging 115 and opening said valve, a vertically-movable rotatable spindle, a rotary fan having inclined blades fixed on said spindle and operating to lift the same by the reaction of the fan against the atmosphere, a pivoted lever 120 engaged by said spindle and operated thereby to throw the valve-operating mechanism out of operation, means for normally holding said lever in position for operating the valve, and means for adjusting the tension of said 125 spring, substantially as described.

11. In a gas-engine, the combination with a cylinder and a reciprocating piston, of a water-jacket surrounding said cylinder and comprising two concentric cylinders detach-

ably secured on the engine-cylinder and closed at their ends, substantially as described.

12. In a gas-engine, the combination with the cylinder and a self-closing gas-supply valve therefor, a vertically-movable, rotatable spindle, a pivoted lever for operating said valve, said lever being cut away to receive said spindle, means for rotating the spindle, and means for moving said spindle vertically, substantially as described.

13. In a gas-engine, the combination with the cylinder and a self-closing gas-supply valve therefor, of a pivoted lever for operating said valve, a vertically-movable rotatable spindle connected to said lever, a rotary fan having inclined blades attached to said

spindle and operating against the atmosphere to lift said spindle, and means for rotating the spindle, substantially as described. ^{2c}

14. In a gas-engine, the combination with the cylinder provided with an annular flange at one end, of a water-jacket surrounding said cylinder and having two concentric walls and a head, and means for securing the open ²⁵ end of the water-jacket to the said flange, substantially as described.

In testimony whereof I have hereunto set my hand in presence of two subscribing witnesses.
